United States Patent

Des. 236,011
Patented July 22, 1975

236,011

CAGE FOR DOMESTIC ANIMALS OR SIMILAR ARTICLE

Dwain F. Roche, New Strawn, Kans., assignor to
Herbert R. Amann, Greenwood, Mo.

Filed Aug. 31, 1972, Ser. No. 285,324

Term of patent 14 years

Int. Cl. D30—02

U.S. Cl. D30—1

FIG. 1 is a front elevational view of a cage for domestic animals or similar article, showing my new design;

FIG. 2 is a top plan view thereof;

FIG. 3 is a right side elevational view; and

FIG. 4 is a left side elevational view.

I claim:

The ornamental design for a cage for domestic animals or similar article, as shown and described.
